UNITED STATES PATENT OFFICE

JAMES H. WYATT, OF PHILADELPHIA, PENNSYLVANIA, ASSIGNOR TO WILLIAM M. SCOTT, OF PHILADELPHIA, PENNSYLVANIA.

SNAP-SWITCH.

No. 921,050.

Specification of Letters Patent.

Patented May 11, 1909.

Application filed October 22, 1908. Serial No. 458,919.

To all whom it may concern:

Be it known that I, JAMES H. WYATT, a citizen of the United States, residing in the city and county of Philadelphia, State of Pennsylvania, have invented a certain new and useful Improvement in Snap-Switches, of which the following is a specification.

My invention relates to an electrical switch, and more particularly to a snap switch of the type to be operated by push button or the like.

My invention relates to a two button snap switch of the type described in my application Serial No. 429,608, filed April 28, 1908, and resides in an improvement upon or modification of the switch of my said prior application.

For an illustration of one of the forms my invention may take, reference is to be had to the accompanying drawing, in which:

Figure 1 is a vertical sectional view through the cover and switch box, the switch parts being shown in elevation. Fig. 2 is a side elevation of the switch mechanism isolated, switch contacts being omitted and parts cut away for the sake of clearness. Fig. 3 is a vertical elevational view looking at the side of the mechanism shown in Fig. 2. Fig. 4 is an end elevational view of the button arm or spring winding member. Fig. 5 is a plan view of the same. Fig. 6 is a side elevational view of the same. Fig. 7 is a front elevational view of the detent or latch member. Fig. 8 is an edge view of the same. Fig. 9 is an edge view of a portion of one of the switch spindle or pivot supports. Fig. 10 is a front view of the same.

Referring to the drawing, B is a receptacle or casing of insulating material, such as molded porcelain, adapted to contain and surround the switch contacts and switch mechanism. Upon the top of the receptacle B is secured the base plate 1 from which is supported the entire switch mechanism, with the exception of the stationary contacts. A finishing plate 2 is secured to the base plate 1.

Through apertures in the base plate 1 and the finishing plate 2 extend the two push buttons 3 and 4, mounted respectively upon the vertically disposed metallic members 5

and 6. The member 6 is pivoted at 7 to the arm 8 of the spring winding member 9. The other button member 5 is pivoted at 10 to the other end of the arm 8 of the spring winding member.

Extending downwardly from the under side of the base plate 1 and secured to or integral therewith, and disposed between the two buttons 3 and 4, are the two switch supporting members 11 and 12. Extending horizontally between the supporting members 11 and 12 approximate their lower ends, and mounted in them, is the switch supporting pivot or spindle 13. The button arm or spring winding member 9 has secured thereto a bushing 14, as shown in Fig. 6, through which the spindle or shaft 13 passes. A coiled spring 15 surrounds the bushing 14, while the ends 16 of such spring extend downwardly one on each side of the horizontal lug or projection 17 formed on the spring winding member 9. These ends 16 of the coiled spring 15 also engage or straddle the horizontal portion 18 of the contact carrying member having the end portions 19, 19 pivoted upon the spindle or shaft 13 and adapted to have secured thereto, but insulated therefrom, the movable switch contacts. The lug or projection 17 on the spring winding member extends substantially parallel with the portion 18 of the contact carrying member, as seen in Fig. 3, the lug 17 intervening between the spindle 13 and the portion 18 of the contact carrying member, and its outer end extending into the path of the ears or lugs 22 of the detent member 23 hereafter described.

To the left of the spring winding member 9, as viewed in Fig. 3, and surrounding the shaft 13, is a second coiled spring 20 whose two ends 21, 21 engage upon the tops of the lugs or ears 22, 22 of the detent or latch member 23, the latter shown isolated in Figs. 7 and 8. This detent or latch member 23 has an elongated aperture 24 which loosely embraces a bushing carried on the pivot or spindle 13, the detent member 23 being by this means capable of rotation upon the bushing and able to reciprocate radially relatively thereto. In its lower side the detent

member 23 has a notch 25 adapted to embrace the portion 18 of the contact carrying member, so that the detent member 23 and the contact member rotate with each other, 5 but the member 23 is capable also of radially reciprocating movement. In the upper portion of the detent member 23 are formed the notches 26 connected by the narrow slot 27, thus forming shoulders 28, 28. The spring 20 10 is so tensioned that its ends 21, 21, engaging upon the tops of the ears 22, 22, tend to depress and hold depressed the entire detent or latch member 23.

Upon the switch supporting member 11 is 15 a lug 29, either struck up from the body of the material of the member 11, or consisting of an independent piece secured thereon, such lug 29 being of a height or thickness in a direction radial to the spindle 13 as to 20 freely pass through the slot 27, and of a width to allow its engaging in either of the notches 26, 26 of the detent member 23.

The stationary switch contacts are shown in Fig. 1 at 30 and 31, mechanically and electrically secured to the posts 32 fastened in recesses in the receptacle B by screws 33. Upon the tops of the posts 32, 32 are the binding screws 34 to receive and secure the circuit wires. Coöperating with the stationary switch contacts 30 and 31 are the movable switch contacts 35 and 36, secured at 37, 37 by eyelets, rivets or the like, suitable insulating material intervening, to the end heads 19 of the contact carrying member 35 18.

The operation is as follows: With the parts in open circuit position, to close circuit the operator depresses button 3. When it has been depressed to the position shown in 40 Fig. 2, the parts are about to snap to circuit closing position. As the operator begins to depress the button 3 the arm 8, of the spring winding member 9, is rotated in a counter-clockwise direction, as viewed in Fig. 2, thus 45 winding up the spring 15 whose one end 16 is carried around by the spring winding member and whose other member is held against the contact carrying member 18, the latter being held locked by the detent or latch plate 50 23 having the lug 29 on the switch supporting member 11 engaging in one of its notches. As the depression of the button 3 continues and the tension on the spring 15 is progressively increased, the lug or projection 17 on 55 the spring winding member 9, which serves to engage the end of the spring to wind the same, engages the under side of an ear or lug 22 of the latch plate 23 to actuate the same in opposition to the spring 20 which tends to 60 hold the latch or detent member 23 depressed. This engagement of the ear or lug 22 by the projection or lug 17 of the spring winding member does not occur, however, until practically the end of the button movement or 65 spring winding movement. Then, when the

detent member 23 is so lifted the notch 26 recedes from the lug 29, and the engagement between the lug 29 and the shoulder 28 ceases, and the detent member 23 and the contact carrying member 18 are snapped to 70 circuit closing position, by a rotary movement, the slot 27 in the detent member 23 allowing the movement over or past the lug 29. At the end of such movement, the spring 20 again depresses the detent member 75 23, so that the lug 29 now engages in the other notch 26. To limit the angular travel of the contact carrying member, the switch supporting member 11 is provided with shoulders 37 between which the oscillation of 80 the contact carrying member occurs.

For reverse operation, the button 4 is depressed and the same cycle of oscillations is repeated, the contacts snapping to open circuit position. 85

What I claim is:

1. In a snap switch, the combination with a pivoted contact carrying member, of a detent member engaging and rotating with the same, ears upon said detent member, a coiled 90 spring having its ends engaging said ears to hold said detent member depressed, an operating spring, a spring winding member, and a projection on said spring winding member for engaging said operating spring and for 95 engaging said ears upon said detent member to shift the same.

2. In a snap switch, the combination with a pivoted contact carrying member, of a detent member engaging and rotating with the 100 same, ears upon said detent member, a spring engaging said ears to hold said detent member in normal position, an operating spring, a spring winding member, and a projection on 105 said spring winding member disposed between said contact carrying member and its axis of movement for engaging said ears upon said detent member to shift the same.

3. In a snap switch, the combination with a pivoted contact carrying member, of an 110 operating spring, a spring winding member, a detent member engaging said contact carrying member and adapted to rotate therewith, ears upon said detent member, a spring engaging said ears to hold said detent member depressed, a fixed member, a lug thereon, 115 notches in said detent member adapted to receive said lug, and means on said spring winding member for actuating said detent member to release said contact carrying member. 120

4. In a snap switch, the combination with a pivoted contact carrying member, of a detent member engaging and rotating with the same, notches in said detent member, a slot 125 uniting said notches, ears upon said detent member, a lug on a fixed member adapted to engage in said notches and to pass through said slot, a coiled spring engaging said ears to hold said detent member in position for said 130

lug to engage in a notch, an operating spring, a spring winding member, and a projection on said spring winding member for engaging said operating spring and for engaging said ears upon said detent member to shift the same.

In testimony whereof I have hereunto af-

fixed my signature in the presence of the two subscribing witnesses.

JAMES H. WYATT.
